ATTORNEY.

UNITED STATES PATENT OFFICE.

CHARLES C. MILLER, OF FORT WAYNE, INDIANA.

DISPLAY CARTON.

Application filed July 26, 1926. Serial No. 124,792.

The invention relates to display cartons and its object is to provide a simple and cheap carton in which to enclose articles of various kinds, the cover for which may also 5 serve as a means by which to support the receptacle in inclined position.

The invention consists of an open top receptacle and a cover therefor attached to the bottom of the receptacle and foldable over 10 and onto the receptacle or under the same to support it, opposite sides of the cover being diagonally foldable to cause the top of the cover to incline in the supporting position of the cover.

15 The invention is illustrated in the accompanying drawings, in which Figure 1 is a perspective view of the carton in closed condition; Fig. 2 a cross-sectional view on line 2-2 of Fig. 1; Fig. 3 a plan view of the 20 carton in open condition; Fig. 4 a side elevational view of the same, and Fig. 5 an exaggerated side elevational view of the carton in display condition.

In the illustrative embodiment of the 25 invention, the receptacle portion 1 of the carton consists of a bottom 2 and integral side walls 3, 4, 5 and 6, the walls being connected at the corners in suitable manner, such as by the tapes 7.

30 The cover portion 8 consists of a top 9 and three walls 10, 11 and 12. The forward ends of the walls 11 and 12 are suitably secured to the wall 10 as by the tapes 13. Each wall 11 and 12 is cut-scored on its outer side 35 from the upper front corner toward the lower rear corner, as shown at 14. The top is extended beyond the inner or rear ends of the walls 11 and 12, the extension 15 being suitably secured to the lower face of the 40 bottom 2 of the receptacle. The extension is scored transversely at the ends of the walls 11 and 12, as indicated at 16, and also adjacent to the wall 6 of the receptacle so that it will fold upwardly on the latter scoring 45 and the cover will fold on the scoring 16 over the top of the receptacle and it may be folded on said scoring under the receptacle.

A display panel 17 is secured to the in-

ner face of the wall 6 of the receptacle and to the lower face of the top of the cover, the 50 panel being scored transversely, if necessary, in the vicinity of its middle portion so that it will fold at said point when the cover is closed on the receptacle, as shown in Fig. 2.

When the cover is disposed on the receptacle the walls 10, 11 and 12 contact with or 55 oppose the walls 3, 4 and 5, and the extension 15 abuts against the folded display panel. The receptacle is thereby fully closed or substantially enclosed by the cover.

60 When it is desired to display the contents of the receptacle the cover is turned on the scoring 16 under the extension 15 and the bottom of the receptacle. The side walls 11 and 12 are collapsed on the diagonal cut 65 scorings 14 and the triangular walls now formed support the receptacle in inclined position. The panel 17 is drawn tight by the folding of the cover under the extension 15 so that the advertising matter imprinted or 70 otherwise placed on the panel is in plain view and attracts attention.

What I claim is:

1. A display carton consisting of a receptacle portion and a cover portion having its 75 top extended and secured to the bottom of the receptacle, a display panel secured to one wall of the receptacle and to the said top, and the cover being foldable on the said extension either over and onto the receptacle or under the receptacle to support it.

2. A display carton consisting of a receptacle portion and a cover portion having its top extended and secured to the bottom of the receptacle, a display panel secured 80 to one wall of the receptacle and to the said top, and the cover being foldable on the said extension either over and onto the receptacle or under the receptacle and the cover having two opposite vertical walls collapsible upon diagonal lines to support the receptacle in inclined position.

85 In witness whereof I have hereunto signed my name this 8th day of July, 1926.

CHARLES C. MILLER.
